UNITED STATES PATENT OFFICE.

EMANUEL FOLGMAN, OF BROOKLYN, NEW YORK.

CLEAN-OUT FOR BURNERS.

1,379,544.

Specification of Letters Patent. Patented May 24, 1921.

Application filed January 26, 1920. Serial No. 354,098.

To all whom it may concern:

Be it known that I, EMANUEL FOLGMAN, a citizen of the United States, and a resident of the city of New York, borough of Brooklyn, in the county of Kings and State of New York, have invented a new and Improved Clean-Out for Burners, of which the following is a full, clear, and exact description.

10 The present invention relates to new and useful improvements in self-blown torches, and it pertains more particularly to an improvement on the device disclosed in United States Patent No. 1,330,696, granted to me 15 February 10, 1920, to which cross reference is here made.

In the device described in the patent above mentioned, there is a main receptacle, a starting tube, a retort tube, and a burner tube. The burner tube is substantially U-shaped in form and is provided with a burner opening through which the gas passes in the presence of the flame of the starting tube and is ignited. In actual practice it has been found that from various reasons owing to its constricted size, the burner tube becomes clogged or choked, and its peculiar construction and arrangement prevent of its being cleaned without the entire removal thereof.

20 It is the primary object of the present invention to so construct the plugs or caps closing the ends of the fuel and retort tubes that a passage is presented in alinement 25 with the passage through the constricted burner tube in order to facilitate the cleaning thereof.

With the above and other objects in view, reference is had to the accompanying drawings in which—

Figure 1 is a side elevation of a torch constructed and arranged in accordance with the present invention;

Fig. 2 is a front elevation thereof, and 45 Fig. 3 is a detail sectional view taken on the line 3—3 of Fig. 2.

Referring more specifically to the drawings, the reference character 5 designates a fuel receptacle, and projecting from the upper end thereof is a centrally disposed starting tube 6. This tube 6 is bent outwardly as shown in Fig. 1, and is filled by a wick 7, said tube projecting downwardly into the receptacle 5 a sufficient distance to permit 50 of a thorough saturation of the wick 7 by the fuel contained in the main receptacle 5.

Projecting from the top wall of the receptacle 5 are two tubes 8, and said tubes are curved upwardly and outwardly in such a manner that they overlie the starting tube 6, as shown in Figs. 1 and 2. The reference character 9 designates a substantially U-shaped burner tube, and said burner tube underlies the retort tube 8 and overlies the burner portion of the starting tube 6, as shown in Fig. 1. This burner tube 9 is provided intermediate of its ends with a burner opening 10, and said burner opening 10 is positioned in such a manner that the gas generated in the retort tubes 8 will be projected transversely of the burner end of the starting tube 6.

By reference to Fig. 3, it will be noted that each of the retort tubes 8 has its outer end closed by means of a plug 12, which is 75 suitably secured within its retort. This plug is provided with a passage 13, which extends therethrough in substantial alinement with the axis of its respective retort tube 8, said passage permitting of the insertion of a suitable tool used to position the wick 14 within the retort tube 8. Each passage 13 is adapted to be closed by means of a screw 15, it being understood that a portion of said passage is internally threaded 80 to receive said screw. Passing through the plug 12 from the top to the bottom thereof, is a passage 16. Removably secured as by threaded engagement with the interior of the passage 16 at the upper end thereof, is a 90 screw 17, and said screw is adapted to serve as the closing medium of said passage. The lower end of the passage 16 is enlarged as at 18, and this enlarged portion 18 is adapted to receive the end 19 of the adjacent leg 95 of the U-shaped burner tube 9.

It is to be understood that the construction shown in Fig. 3 is the same on the free end of each of the tubes 8, and that the end of each of the legs of the U-shaped burner tube 9 is bent upwardly as indicated by the reference character 20 to provide for its attachment within the enlarged portion 18 of the passage 16 of its adjacent plug 16. By this construction it will be apparent that 105 should the burner tube 9 become choked or stopped up, upon removing the screws 17, a suitable flexible wire or other cleaning tool may be passed through the passages 16 and the passage of the burner tube 9, to remove 110 the foreign deposits within the tube and thereby thoroughly clean the same.

Claims:

1. In a self-blowing torch, a plurality of retort tubes, a burner tube supported by the retort tubes, said burner tube having a passage therethrough, and plugs secured to the burner tube and closing the ends of the retort tubes, said plugs being provided with passages in alinement with the passage through the burner tube.
- 10 2. In a self-blowing torch, a plurality of retort tubes, a burner tube supported by the retort tubes, a plug closing the end of each of said retort tubes, said plugs being provided with a plurality of right angular passages which passed therethrough and establish communication between the retort tubes and the burner tubes, and means for closing that portion of the passages in the outer walls of the closing plugs.
- 15 3. In a self-blowing torch, a plurality of retort tubes, plug members supported in the ends of said retort tubes, a burner tube hav-

ing a passage therein, said plug members being provided with a plurality of right angular passages arranged within said plug members and adapted to establish communication between the retort tubes and the burner tube, one of the passages of the plug members being arranged in alinement with the passage through the burner tube, and means for closing a portion of each of said passages.

4. In a self-blowing torch, a plurality of retort tubes, a plug for closing the open end of each of said retort tubes and provided with a plurality of angular passages which are adapted to establish communication between the retort tube and the burner tube, and are adapted to permit of the insertion of a cleaning tool to the burner tube and retort tube, and screw-threaded elements for closing the open end of each of said passages, substantially as described.

EMANUEL FOLGMAN.
